UNITED STATES PATENT OFFICE.

WINFIELD YOST, OF MONTREAL, QUEBEC, CANADA, ASSIGNOR TO NATIONAL DUMP CAR COMPANY, A CORPORATION OF MAINE.

DUMP-CAR.

992,625.

Specification of Letters Patent. Patented May 16, 1911.

Application filed April 20, 1907, Serial No. 369,289. Renewed October 20, 1909. Serial No. 523,703.

To all whom it may concern:

Be it known that I, WINFIELD Yost, a citizen of the United States, residing at Montreal, in the Province of Quebec, Dominion 5 of Canada, have invented certain new and useful Improvements in Dump-Cars, of which the following is a specification.

My invention relates to dump cars, especially to that type of car provided with 10 dumping doors in its bottom; and has for its object to provide this type of car with an improved door operating mechanism and with other improvements hereinafter set forth.

15 My invention consists in the details and combinations hereinafter described and claimed.

In the accompanying drawings—Figure 1 is a side elevation of a portion of a dump-car embodying my invention. Fig. 2 is an 20 end view thereof. Fig. 3 is a transverse sectional view, showing at the left a section of the car near the center thereof and at the right a section of the car at the intermediate 25 cross beam. Fig. 4 is a top plan view of a portion of the underframe, partly in section. Fig. 5 is a detail showing a portion of the 30 operating mechanism. Fig. 6 is a section on the line 6 of Fig. 5. Fig. 7 is a section on the line 7 of Fig. 5.

In the drawings, 1 indicates the metallic center sills of the car, which may be of any desired form. I have shown these sills as composed of longitudinal plates provided 35 with angle bars extending along the upper and lower edges thereof connected by suitable top and bottom plates to form a box girder.

40 2 indicates the transverse members of the underframe provided along their lower edges with angle irons 3 and on their upper edges with angle irons 4, these cross beams being suitably connected to the center sill.

5 45 5 indicates one of the dumping doors, these doors composing substantially the entire bottom of the car. These doors are provided along their front and rear edges with angle brace members 6 and are hinged at 7 to the center sill. Attached to the under side 50 of the door is an inclined track 8 and attached to the underframe of the car is an inclined track 9, this track being connected—as shown—either to a gusset plate 10 connecting the side stakes to a transverse mem-

ber of the underframe and projecting below the underframe—as shown at the left in Fig. 3—or to the underframe by means of a depending plate 11. It will be noted that the plate 10 forms a connection between the cross tie and side stake, and a gusset for 55 the ends of the cross tie firmly bracing and supporting the parts at this point. Mounted upon the track 9 is a shaft 12 extending longitudinally of the car. The gusset plates 10 not only serve as a connection between the 60 upper and lower cords of the cross members and the side stake, but also serve as stops for the inner ends of the shafts 12. It will be understood of course that in cars of this 65 type half of the doors are operated from each end of the car, each shaft 12 extending 70 inward from the end of the car to a point adjacent the center thereof. The gusset 10 projects downward sufficiently to prevent longitudinal movement of the shafts 12, as 75 particularly illustrated at the left-hand of Fig. 3 adjacent the upper part of the supporting track 9. Upon this shaft the inclined track on the under side of the door rests, so that as the shaft is moved upon the 80 track 9 the door is opened and closed, depending upon the direction of movement of the shaft. This combination of the inclined tracks and the movable shaft for operating 85 the dumping door is not new with me, but is a well-known method of operating such dumping doors used in cars of the "National" type.

The shaft 12 is squared at its outer end and carries thereon the two ratchet wheels 90 21, 22 having the collars 21' and 22' respectively. These collars are placed in proximity the one to the other and form a sliding surface for the operating lever 15, said lever being loosely mounted on these collars. A 95 pawl 33 pivoted on the lever engages the ratchet wheel 21 to operate the shaft as the lever is moved back and forth in a manner which will be readily understood. It will be observed that the track 9 is provided at 100 its forward end with a horizontal portion upon which the shaft rests when the doors are in closed position. The shaft in this position forms a support for the door and, being locked against movement by a means 105 hereinafter described, forms an efficient locked support which cannot be thrown out of position, except through the positive un-

locking operation of the shaft. In order to secure the shaft in its upper position, as well as to hold it at any intermediate point during the closing of the door, I provide 5 upon the end of the shaft a second ratchet wheel 22 fixed thereto. Mounted also upon the end of the shaft is a plate 17 through which the shaft passes and at the opposite end of this plate 17 is a plate 18 of a general 10 U-shape surrounding the plate 17. The bolt 34 passes through the plate 17 as well as the U-shaped plate and upon this bolt 34 between the legs of the U-shaped plate is mounted a roller 35 which travels upon the 15 track 9. A plate 23 is mounted adjacent one end of the supporting shaft, and a bent plate 19 having an upwardly extending vertical portion 20 is connected to this plate 23, the end of the shaft passing also through this 20 vertical portion.

It will now be seen that the plate 17, together with the plates 18 and 19, forms a stirrup traveling upon the track 9, the shaft and the roller 34 forming a rolling support 25 for this stirrup. It will also be seen that the ratchet wheels upon the shaft are carried in this stirrup at one end thereof, while a detent pawl 4 pivoted to the upper leg of the U-shaped plate 18 is carried at the other 30 end thereof. This detent pawl 4 acts as a detent to prevent the backward movement of the shaft when the latter is being rotated in a direction to close the door. When the door is closed it is desirable to provide some 35 means for holding the detent pawl in locking engagement with its ratchet wheel 22. For this purpose I provide upon the operating lever 15 a projection 24 adapted to engage the pawl 4 when the doors are in closed position, as shown in Fig. 2. It will thus be 40 seen that it is impossible to release the pawl 4 from engagement with the ratchet wheel until the lever 15 has first been raised away to approximately a vertical position.

45 The stirrup extending from the outside of the ratchet wheels to the inside of the rail and traveling upon the rail serves as a guide to prevent longitudinal movement of the shaft and also serves to keep the ratchets in 50 positive relation to each other.

The end sill of my car comprises a plate 55 bent outwardly at its central point, this plate being provided along its upper edge with an angle bar 26 riveted to the plate 25 and along its inner upper edges with angle bars 32 on each side of the center sill. Gusset plates 31 connect the end sill to the center sill, these plates 31 being riveted to the angle bars 32 and to the center sill, respectively.

60 This forms a very strong and secure arrangement at the end sill and prevents the buckling of the end sill and also prevents the draft sills from spreading or buckling. At the corners of the car I provide a gusset 65 plate 27, extending down beyond the floor

line, this gusset plate being suitably connected to the end sill by angle pieces 28 on the exterior and by channel pieces 29 on the interior of the end sill, and to this gusset plate 27 is attached the push pole pocket 38, 70 this push pole pocket being also attached to the bottom angle 39 of the side girder, whereby the strain of the corner is thrown upon the side girder direct.

In order to insure the rotation of the operating shaft, I provide chains 13 and 14, the chains 14 being wound upon the shaft when the latter is in closed position while the chain 13 is unwound. As the shaft rotates the chain 13 is wound and the chain 14 unwound. This arrangement of chains is the same as shown in the United States Patent to Hart & Maltby No. 780,747.

It will be seen that I have provided a car with a very simple and efficient operating 85 mechanism in which the operating shaft is guided, longitudinal movement thereof prevented, and in which the various parts of the car are strengthened to resist the shocks and strains incident to service. It is believed 90 that the operation of my car may be understood without further description.

I claim:

1. In a car of the class described, a floor comprising hinged dumping doors, a track 95 beneath said doors, a shaft movable upon said track to support and operate said doors, operating means for said shaft, a stirrup mounted upon said shaft and having a part engaging said track, and a detent carried 100 by said stirrup and coöperating with the shaft.

2. A car of the class described, having a floor comprising hinged dumping doors, a movable shaft mounted in the underframe 105 of the car for supporting and operating the doors, operating means mounted upon the end of the shaft, a stirrup also mounted on the end of the shaft and engaging the track, and a detent carried by the stirrup and co- 110 operating with the shaft to control the shaft during its door closing movement.

3. A car of the class described, having a floor comprising hinged dumping doors, a movable shaft mounted in the underframe 115 of the car for supporting and operating the doors, operating means mounted upon the shaft, a detent in coöperative relation with the shaft for controlling the shaft in its upward movement, and a locking device on the 120 operating means engaging the detent in one position of the operating means.

4. A car of the class described, having a floor comprising hinged dumping doors, a movable shaft mounted in the underframe 125 of the car for supporting and operating the doors, ratchets mounted upon the end of the shaft, an operating lever also mounted on the end of the shaft in coöperative relation with one of the ratchets, a detent in coöper- 130

ative relation with the other ratchet, and a projection on the lever engaging the detent in one position of the lever.

5. A railway car having its side girder comprising a bottom angle bar extending beyond the end of the side girder, and a gusset plate connected to the side girder and to the extension of the angle bar, said gusset plate extending below the side of the car and being connected to the end sill. 10

6. A railway car having its side girder comprising a bottom angle bar extending beyond the end of the side girder, a gusset plate connected to the side girder and to the extension of the angle bar, said gusset plate extending below the side of the car and being connected to the end sill, and a push pole pocket connected to the lower end of the gusset plate and to the angle bar extension of the side girder. 15

7. A railway car having the lower member of its side extending beyond the end of the side, a depending plate connected to the extension of the side, and a push pole pocket connected to the plate and to the extension of the side. 20

8. An operating device for hinged doors of dump cars, comprising a traveling shaft, operating mechanism upon the end of the 30 shaft comprising ratchet wheels, a track upon which the shaft travels, and a stirrup upon the end of the shaft embracing the ratchet wheels and engaging the track to guide the operating devices and to preserve 35 the ratchet wheels in positive relation to each other.

9. In a railway car side stakes, transverse sills, each transverse sill comprising upper and lower chords, and gusset plates secured 40 to said side stakes and upper and lower

chords and forming the connection between said chords.

10. In a dump car, a center sill, cross members, side stakes, a floor provided with dump doors, tracks beneath the floor level, reciprocating shafts supported on said tracks and extending inwardly from the ends of the car to points adjacent the center thereof, gusset plates secured to the middle side stakes and cross members, said gusset plates affording support for the central tracks and forming stops for the ends of said reciprocating shafts. 45

11. In a dump car, a center sill, cross members, side stakes, a floor provided with dump doors, tracks beneath the floor level, reciprocating shafts supported on said tracks and extending inwardly from the ends of the car to points adjacent the center thereof, gusset plates secured to the middle side stakes and cross members, said gusset plates extending below said cross members and affording support for the central tracks and forming stops for the ends of said reciprocating shafts. 50

12. In a railway car, a side wall, an end wall, a gusset plate secured to the side wall and end sill and depending below the car side, and a push pole pocket secured to the depending part of said gusset plate. 55

13. In a dump car, a rotary operating shaft, a detent ratchet and a power ratchet non-rotatably engaging said shaft, and a U-shaped stirrup engaging said shaft outside of said ratchets and serving to hold 75 them in fixed relation to each other.

WINFIELD YOST.
